FREDERICK W. BROCKSIEPER, OF NEW HAVEN, CONNECTICUT, ASSIGNOR
TO SARGENT & CO., OF SAME PLACE.

Design No. 4,364, dated September 27, 1870.

DESIGN FOR A DOOR-PULL.

The Schedule referred to in these Letters Patent and making part of the same

To all whom it may concern:

Be it known that I, FREDERICK W. BROCKSIEPER, of New Haven, in the county of New Haven and State of Connecticut, have invented a new Design for Door-Pull; and I do hereby declare the following, when taken in connection with the accompanying illustration, to be a full, clear, and exact description of the same, and which said illustration constitutes part of this specification, and represents a perspective view.

This invention relates to a design for the article of manufacture known to the trade as door-pulls, that is to say, the handle fixed to a door, by which the door may be moved, and consists in the peculiar configuration and ornamentation of the parts, as fully shown in the accompanying photographic illustration, to which reference is made.

I claim as my invention—

The design for door-pull, as shown.

F. W. BROCKSIEPER.
